UNITED STATES PATENT OFFICE.

MILO HARRIS, OF JAMESTOWN, NEW YORK, ASSIGNOR OF ONE-HALF TO
NATHANIEL E. THOMAS, OF SAME PLACE.

PILLOW-SHAM HOLDER.

SPECIFICATION forming part of Letters Patent No. 278,705, dated June 5, 1883.

Application filed November 23, 1882. (No model.)

To all whom it may concern:

Be it known that I, MILO HARRIS, of Jamestown, in the county of Chautauqua and State of New York, have invented certain new and useful Improvements in Pillow-Sham Holders; and I do hereby declare that the following is a full, clear, and exact description of the invention, which will enable others skilled in the art to which it appertains to make and use the same, reference being had to the accompanying drawings, which form a part of this specification.

The object of my invention is to make a cheap and efficient pillow-sham holder, and one which may be used as a mosquito-bar holder at the same time and at no extra expense; and the invention consists in the several parts set forth in the following description and accompanying drawings, in which—

Figure 1 shows the invention as applied. Fig. 2 shows sectional view of roll and bracket. Fig. 3 shows one of the brackets; Fig. 4, a modification which may be applied at the end of roller.

In the drawings, A represents a bedstead. B is a wood roller or stretcher crossing the head of the bedstead, and is held in position by the brackets C C. These may be stamped out of heavy sheet metal; but I generally have them cast with screw-holes, so they can be attached to head board or posts, as desired, and one bracket has a round hole large enough for the roller or stretcher to work in and the other a square hole or mortise for the same. The roller is made square near one end and of smaller circumference and round next to the knobs a a, which are screwed on each end, and serve to keep the roller from slipping too far endwise, and hold the roller from coming out of the brackets. These knobs are also used to turn the roller when desired.

D D D are rods or spring-wires screwed into the roller, and extend from it a suitable distance, and have a cross-wire at their end. I sometimes set the outside wires to project outwardly, and instead of using the cross-wire I use a strong cord and draw the wire in somewhat, and the spring of the wire draws the cord to the proper tension. The roller and rods form a suitable frame for holding the pillow-sham, and these are secured to the roller

and frame by bands or any other suitable means, and when desired to operate the device you grasp the knob and turn the roller, so the rods and shams stand upright, and the 55 roller is pushed endwise, the square of the roller fitting the square of the bracket, and the whole is held up and out of way when using the bed, and can as readily be slipped endwise off the square, and is rolled down, carrying the shams back over the pillows, as before. When desired to use as a mosquito-bar holder, the roller is turned till the wire rods are horizontal, and then the roller slipped endwise. The square of roller enters the square 65 of bracket and holds the rods out over the head of the bed. Mosquito-netting of suitable dimensions is thrown over or fastened to the roller and frame, and, coming down on the bed, completes the operation.

Instead of the square being cut on the roller and a square mortise in bracket for holding the frame in an upright or horizontal position, I sometimes use a bracket with cross-mortises, as shown at e, Fig. 4, and put onto the end of 75 roller a flanged casting, c, Fig. 4, to fit said mortise; yet I find the other method cheaper and better.

I claim—

1. In pillow-sham holders, a roller with rods 80 rigidly attached thereto to form a frame for holding the shams, the roller being provided with suitable bearings to rotate in brackets which are securely held to the head of a bedstead, one bracket having a square mortise, the 85 roller having a corresponding square near one end to enter said mortise, for the purpose of holding the frame of sham-holder in an upright or horizontal position, substantially as shown and described, and for the purpose set forth. 90

2. In combination with a bedstead, a pillow-sham holder consisting of roller B, rods D, tie b, and brackets C C, all made and arranged to operate substantially as shown, and for the purpose set forth.

In testimony that I claim the foregoing as my own invention I have hereto affixed my signature in presence of two witnesses.

MILO HARRIS.

Witnesses:

L. E. HARRIS,
L. M. THOMAS.
